DECANTER

Ernest L. Du Pree, Weston, Conn., assignor to Schenley Industries, Inc., New York, N. Y., a corporation of Delaware

Application December 7, 1955, Serial No. 39,207

Term of patent 14 years

(Cl. D58—8)

The opposite side of Figure 1 is the same as the side shown.

I claim:

The ornamental design for a decanter, as shown and described.
